DESIGN FOR A COMBINED COMB AND THINNING RAZOR

Vincent R. Pileggi, Philadelphia, Pa.

Application May 17, 1940, Serial No. 92,419

Term of patent 7 years

To all whom it may concern:

Be it known that I, Vincent R. Pileggi, a citizen of the United States, residing at Philadelphia, in the county of Philadelphia and State of Pennsylvania, have invented a certain new, original, and ornamental Design for a Combined Comb and Thinning Razor, of which the following is a specification, reference being had to the accompanying drawing, forming part thereof.

In the drawing:

Fig. 1 is a side elevational view of a combined comb and thinning razor showing my new design; and

Fig. 2 is an enlarged fragmentary perspective view thereof.

I claim:

The ornamental design for a combined comb and thinning razor, as shown.

VINCENT R. PILEGGI.
